A. P. GRUNN

MIXING APPARATUS

Filed March 15, 1927

UNITED STATES PATENT OFFICE.

ALBERT P. GRUNN, OF CHICAGO, ILLINOIS.

MIXING APPARATUS.

Application filed March 15, 1927. Serial No. 175,498.

The object of the mixing apparatus described and claimed herein is to provide means for the thorough and rapid admixture of the investment compound with which

5 wax dental patterns are "painted" in the preparation of the molds from which the castings are made. The perfection of form of the casting depends upon the formation of a perfectly homogeneous mixture of the 10 investment compound with water and the complete elimination of air bubbles therefrom. The use of an imperfectly mixed investment compound or the presence of air bubbles therein causes irregularities in the 15 form of the casting, and as in this class of work the utmost precision of form is necessary the process of mixing assumes an importance and difficulty not present in work requiring less precision. Exclusion of bubbles and thorough admixture are difficult 20 and not always attainable when hand spatulation is depended on. In my attempts to construct a mechanical mixer I have found that without the provision of means especially adapted to the purpose satisfactory results cannot be accomplished, and it is to the means devised for this purpose that this application for patent is directed.

In the drawings:

30 Figure 1 is a perspective view of the complete structure, the hand piece of a dental engine and the hands of the operator being shown in dotted lines.

Figure 2 is a central longitudinal section 35 through the mixer shown in Figure 1.

Figure 3 is a section on the line 3—3 of Figure 2.

Figure 4 is a section on the line 4—4 of Figure 2.

40 Figure 5 is a side view of the three parts of which the mixer is composed, the parts being separated on an axial line.

The mixer comprises a cylindrical vessel, *a*, open at one end and preferably having the inner surface of the closed end of conical form. The cover, *b*, has a depending flange, *c*, adapted to surround the cylindrical wall of the vessel, and a bayonet joint consisting of a lug, *d*, and slot, *e*, serves to hold the cover in closed position on the vessel. The cover is provided with a central outwardly projecting boss, *g*, through which extends an elongated bearing aperture, *f*. The mixing or spatulation is effected by a 50 rotary spatula comprising a shaft, *h*, with blades projecting radially therefrom. In

the structure illustrated the blades are in two series projecting from diametrically opposite sides of the shaft, the intermediate blades upon each side being opposite the spaces between the blades on the opposite side of the shaft. By this staggered arrangement of the blades the material passing between the blades of one series encounters the blades of the other series thus eliminating the possibility of any of the material escaping thorough spatulation.

I have shown the three lower blades upon each side of the shaft as lying in the plane of the axis of the shaft and the uppermost 70 blades adjacent the cover as oppositely inclined to the plane of the axis of the shaft whereby rotation of the shaft in the direction of rotation of the shaft of the dental engine, to which the mixer shaft is designed 75 to be clutched, will force the material in the mixer toward the closed end thereof and away from the cover and the bearing aperture therein. The position of the lower three blades upon each side of the shaft in the 80 plane of the axis of the shaft facilitates the escape from the investment mixture of air bubbles which have a tendency to adhere to inclined blades. I have found that the provision of two inclined blades adjacent the 85 cover is sufficient to provide circulation of the mixture and to keep it away from the cover and from the shaft bearing therein.

The bearing aperture, *f*, in the cover is counter-sunk at its inner end as shown at *i* 90 to form a seat for a projecting annular shoulder, *k*, formed on the shaft, *h*. The bearing surfaces of the shoulder, *k*, and counter-sink *i* are shown as spherical in form, thereby permitting some variation in 95 the angular position of the shaft without destroying contact between the bearing surfaces referred to. The distance from the shoulder *k* to the inner end of the shaft is slightly less than the distance from the bearing surface of the counter-sink *i* on the cover to the inner end of the cylindrical vessel when the cover is in position as shown in Figure 2, thereby permitting some clearance 105 between the inner end of the rotary spatula and the closed end of the vessel. As above stated, the inclination of the upper blades, *l*, *m*, forces the material in the mixer toward the closed end and away from the cover, and the reaction upon the rotary spatula blades, 110 *l*, *m*, impels the rotary spatula toward the cover thereby establishing close sealing con-

2
tact between the bearing surfaces on the shoulder *k* and counter-sink *i* and at the same time establishing working clearance between the inner end of the rotary spatula 5 and the closed end of the cylindrical vessel *a*.

As shown in Figure 1, the outer projecting end of the shaft is designed to be clutched to the shaft in the hand piece of the dental engine indicated at *o*. In operation the operator holds the hand piece with one hand 10 and the vessel *a* with the other hand. The elongated bearing *f* and counter-sink bearing *i* dispense with the necessity of any bearing at the inner end of the rotary spatula, and the fact that the three parts of the 15 apparatus are separable when the cover is released from the vessel makes it possible to readily clean all parts of the mechanism each time it is used.

20 I claim:—

In a device of the class described, a cylindrical vessel open at one end, a cover for

said open end, means for detachably securing the cover to the vessel, the cover being provided with a central bearing aperture, a 25 rotary spatula comprising a shaft and radial blades projecting therefrom, said shaft extending through and projecting beyond said bearing aperture and having thereon an annular shoulder of greater diameter than the aperture and adapted to bear against the inner side of the cover thereby restraining the spatula against outward movement but permitting the spatula and cover to be separated, blades on opposite sides of said 30 shaft being oppositely inclined whereby rotation of said spatula in one direction forces said shoulder against the inner side of said cover thereby sealing said vessel during rotation of said spatula.

In testimony whereof, I have subscribed my name.

ALBERT P. GRUNN.
